STANLEY SYKES AND GUY SYKES, OF FLAGSTAFF, ARIZONA.

CARBURETOR.

Application filed June 7, 1923. Serial No. 643,946.

This invention relates to improvements in internal combustion engines, and has particular reference to a carburetor therefor.

An object of the invention is to provide an

improved carburetor of simple and practical construction, wherein the mixture of the fuel and air in the mixing chamber is automatically controlled by the operation of the throttle which regulates the speed of the engine.

Another object is to provide a simple and effective means for automatically operating the needle valve to control the amount of fuel to be supplied to the mixing chamber.

The above and other objects will appear more clearly from the following detail description, when taken in connection with the accompanying drawings, which illustrate a preferred embodiments of the inventive idea.

20 In the drawings—

Figure 1 is a fragmentary side elevation of the carburetor constructed in accordance with the invention;

Figure 2 is a fragmentary top plan view;

25 Figure 3 is a longitudinal section through the mixing chamber;

Figure 4 is an elevational view, partly in section, and taken at right angles to Figure 1; and

30 Figure 5 is a side elevation of the choke valve employed in connection with the invention.

Referring more particularly to the accompanying drawings, the carburetor is shown as comprising a body 6 to which is connected the float chamber 7 having a passage 8 leading therefrom and communicating with the passage 9 in the body 6, which latter passage is controlled by the needle valve 10.

40 Communicating with the passage 9 at a point adjacent the inner end of the needle valve is an air port 11, the size of which may be regulated by a set screw 12 and through which air may enter into the body

45 of the carburetor to mix with the fuel from the float chamber as the same passes the needle valve and enters the outlet pipe 13. As shown in Figure 4, this outlet pipe is extended into a section of the exhaust mani-

50 fold 14 of an engine and terminates in a coil 15 within said manifold, whereby the fuel conveyed through the pipe 13 is heated and vaporized upon passing through said coil 15. Also connected to the coil 15 is an inlet

55 pipe 16 which communicates with one end of a passage 17 in the body of the carburetor, the other end of which has connected thereto a nozzle 18 having a plurality of perforations 19 adjacent the free end thereof.

60 The nozzle 18 projects from the body 6 and into the mixing chamber 20 at the end of said chamber adjoining the body. Intermediate the ends of the mixing chamber the same is provided on opposite sides thereof

65 with air inlet openings 21 through which air may enter into the chamber to mix with the vaporized fuel emitted from the nozzle 18 through the perforations 19 so as to provide a suitable combustible mixture which passes

70 from the mixing chamber into the intake manifold of the engine to which the plate 22 is secured. Rotatable within the mixing chamber 20 is a choke valve 23, of substantially cylindrical formation, having one end

75 cut to provide opposed flanges 24 each having an edge thereto disposed diagonally with respect to the longitudinal axis of the valve and arranged in a plane intersecting the

diagonal edge of the other flange, as illustrated in Fig. 5. The valve is provided with

80 an arm 25 which projects through the mixing chamber 20 and is movable in a slot 26 so that the valve may be rotated in the chamber. Each of the flanges 24 of the

85 valve cooperates with one of the openings 21 in the mixing chamber and is so formed that a rotation of the valve within said chamber will cause the opening 21 to be

90 enlarged or decreased according to the amount of air it is desired to have pass into the mixing chamber when the engine is first

95 started or is being run during extremely cold weather. This choke valve 23 is utilized as an air adjustment independent of that effected by the control mechanism presently

100 to be described.

In order to automatically control the quality of the mixture in accordance with the speed of the engine, the invention fur-

105 ther provides a throttle sleeve 27 which is rotatably mounted upon the mixing chamber 20 and to which is connected a throttle rod 28 utilized to control rotation of the sleeve. It will, of course, be understood that

110 this throttle rod may be controlled in any desired manner to operate the throttle sleeve 27. The sleeve 27 is provided with opposite-

ly disposed openings 29 therein, which register with the openings 21 in the mixing chamber, and as the sleeve 27 is rotated about

115 said mixing chamber the size of the openings

21 will be varied to admit more or less air into said chamber. The rotation of the sleeve 27 is also utilized to control the size of the aperture with which the needle valve 10 is associated, so that when the throttle is operated to increase the speed of the engine, said sleeve will operate the needle valve to enlarge the opening in the passage 9 through which the fuel from the float chamber 7 flows. It will be understood that in thus operating the throttle to increase the speed of the engine, the sleeve 27 will be rotated to enlarge the openings 21 and thus permit of more air entering the mixing chamber. The means for accomplishing the control of the needle valve 10, preferably comprises a cam 30, formed integrally with one end of the sleeve 27 and engaging a roller 31 carried by the free end of a lever 32, pivoted at 33 to a bracket 34 forming a part of the body 6. The upper end of the needle valve 10 extends through a suitable opening formed in the lever 32 and is threaded to receive the nuts 35 against one of which a spring 36 carried by the bracket 34 is engaged to normally force the needle valve downwardly toward its seat and the lever 32 toward its normal position, thus maintaining the roller 31 in engagement with the periphery of the cam 30. The parts are shown in Figure 1 in the positions they assume when the throttle is fully opened and the needle valve 10 is raised to its extreme upper position. It will thus be seen that when the throttle is actuated to decrease the speed of the engine the sleeve 27 will be rotated in a direction to diminish the size of the openings 21 and the cam 30 will likewise be rotated to permit of a lowering of the needle valve 10 and lever 32 under the influence of the spring 36, thus permitting the needle valve to move toward its seat to diminish the size of the orifice through which the fuel in the passage 9 flows.

45. What is claimed is:

1. In a carburetor, a body having a fuel orifice, a mixing chamber having an air

opening in each side, a fuel inlet in said chamber and communicating with said orifice, a needle valve controlling the orifice, 50 a choke valve in the form of a hollow cylinder mounted to turn in the mixing chamber for varying the size of the openings thereof, a throttle valve in the form of a sleeve mounted to turn on the walls of the mixing 55 chamber and having an opening in each side adapted to register with the openings of the mixing chamber, and means for operating the needle valve from the throttle valve.

2. In a carburetor, a body having a fuel 60 orifice, a mixing chamber having oppositely arranged air openings in its sides, a fuel inlet in said chamber and communicating with said orifice, a needle valve controlling the orifice, a tubular choke valve mounted to 65 turn in the mixing chamber and having at one end opposed flanges for varying the size of the openings of the mixing chamber, each flange having an edge disposed diagonally with respect to the longitudinal axis of the 70 valve and arranged in a plane intersecting the diagonal edge of the other flange, a tubular throttle valve mounted to turn on the walls of the mixing chamber and provided with openings adapted to register with the 75 openings thereof, and means for operating the needle valve from the throttle valve.

3. In a carburetor, a body having a fuel orifice, a needle valve controlling the orifice, a lever pivoted to the body and through 80 which the valve stem projects, a roller on the free end of the lever, a spring secured to the body and engaging the valve stem, a mixing chamber communicating with the fuel orifice, a tubular choke valve mounted 85 to turn in the chamber for varying the size of the openings thereof, a sleeve throttle valve mounted to turn on the walls of the mixing chamber and having openings adapted to register with the openings thereof, and a cam on one end of the throttle valve and 90 engaging the roller of said lever.
